UNITED STATES PATENT OFFICE

114,650

DESIGN FOR A GAME TABLE

Pedro G. Valenzuela and Edward S. Castro,
Kapapala, Pahala, Kau, Territory of Hawaii

Application December 12, 1938, Serial No. 81,750

Term of patent 7 years

To all whom it may concern:

Be it known that we, Pedro G. Valenzuela and Edward S. Castro, citizens of the United States of America, residing at Kapapala, Pahala, Kau, Hawaii, have invented a new, original, and ornamental Design for a Game Table, of which the following is a specification, reference being had to the accompanying drawing, forming part thereof, wherein

We claim:

The ornamental design for a game table, as shown.

PEDRO G. VALENZUELA.
EDWARD S. CASTRO.
